UNITED STATES PATENT OFFICE.

HERBERT C. JONES, OF CHICAGO, ILLINOIS.

SOFA-BED.

SPECIFICATION forming part of Letters Patent No. 702,959, dated June 24, 1902.

Application filed October 25, 1901. Serial No. 79,920. (No model.)

To all whom it may concern:

Be it known that I, HERBERT C. JONES, a citizen of the United States, residing at Chicago, in the county of Cook and State of Illinois, have invented certain new and useful Improvements in Sofa-Beds, of which the following is a specification.

The object of this invention is the production of a sofa-bed embodying the improvements hereinafter shown and described.

In the accompanying drawings, Figure 1 is a transverse vertical section through a couch embodying the features of my invention, showing the parts in their relative positions to form a sofa. Fig. 2 is a similar view showing the back partially lowered to form a bed and the other parts in their corresponding positions. Fig. 3 is a view similar to that of the preceding figure, showing the last or final position of the back, also showing the seat lowered on a level with it and the drawer in its outward position. Fig. 4 is a longitudinal vertical section on dotted line 4-4 of Fig. 1. Fig. 5 is a horizontal section on dotted line 5-5 of Fig. 4, the seat and the drawer being removed.

Like letters of reference indicate corresponding parts throughout the several views.

In the embodiment herein shown of this invention I employ a supporting-frame A, composed of the end members A¹ and A², the upright members A³, the rear brace A⁴, and the cross-piece A⁵. Between the rear brace A⁴ and the cross-piece A⁵, I secure the drawer-guides A⁶, and to the inner side of the members A¹ and A² and extending between the rear brace A⁴ and a supporting-block A⁷, fixed to each of the end members A¹ and A², are the rails A⁸, grooved, as at A⁹, to guide the rollers 40 that carry the seat.

The back B has a link connection with the supporting-frame A by means of the two links B', each pivoted to one of the upright members A³ at B² and to one side of the back B at B³. A roller B⁴ at each of the lower rear corners of the back B is adapted to run in the groove A⁹ of the rail A⁸ to support said back during the process of lowering it, as will more fully appear hereinafter.

At each of the lower rear corners of the seat C, I provide a roller C', adapted to run upon the rail A⁸. The back and the seat are piv-

otally connected by a mechanism which will now be described.

To each side of the back B, adjacent to the seat C, a member D is rigidly secured, a similar member D' also being fixed to each side of the seat C, adjacent to the back B. The members D and D' at each side of the sofa-bed are pivotally united by the rivet D². Upon a stud D³ on the member D is pivoted a locking-bar D⁴, adapted to slide within the keeper D⁵ of the member D'. A fixed stud D⁶ on the member D' is adapted to engage a notch D⁷ in said locking-bar D⁴ when the seat and the back are in certain relative positions, and when the seat and the back occupy certain other positions the point D⁸ of a gravity-pawl D⁹, mounted upon a stud D¹⁰ on the member D', will engage the teeth D¹¹ of the locking-bar D⁴. When the locking-bar lies with its notch D⁷ in engagement with the fixed stud D⁶, the back B and the seat C are locked from outward movement upon their connecting hinge-joint.

The drawer E is supported upon the guides A⁶ and is provided at each of its forward lower corners with the caster E', adapted to support the front end of said drawer when the latter is extended. Upon a supporting-block E², secured to each side of the drawer, near the rear thereof, is pivotally mounted a connecting-link E³, the other end of said link being pivotally connected with the link B', intermediate the ends of the latter.

To lower the back B from the position it is shown to occupy in Fig. 1, the seat C is drawn slightly forward and raised to a vertical position. This movement withdraws the support of the stud D⁶ from the back B, which latter descends by gravity, while at the same time the link connection between said back and the frame and the pivotal connection between the back and the seat cause said seat and said back to move forward upon the rails A⁸. By reason of its link connection with the back B the drawer E will also be projected forward upon its guides A⁶. The seat may now be lowered from its vertical position by moving the upper end of said seat slightly backward, which movement withdraws the stud D⁶ from the notch D⁷ of the locking-bar D⁴ and permits the gravity-pawl D⁹ to engage one of the teeth D¹¹ of said locking-bar. A

forward movement of the upper end of the seat will now cause the gravity-pawl to raise the free end of the locking-bar to a height which permits said bar to slide over the stud

- 5 D⁶ without being engaged by said stud, when the seat may be lowered to the position it is represented as occupying in Fig. 3. When it is desirable to raise the back B to an upright position, the forward end of the seat C is 10 raised until the locking-bar D⁴ is drawn rearward in the keeper D⁵ a sufficient distance to permit the fixed stud D⁶ to enter the notch D⁷ in said locking-bar. Upon returning the seat to its normal position the back B will be 15 raised and the drawer E will be slid inward upon the guides A⁶. Free access may be had to the interior of the drawer by raising the seat.

20 When the parts are in the position indicated in Fig. 1, the back must first be tilted slightly forward to release the engagement of the locking-bar D⁴.

25 It is clear that slight changes may be resorted to in the general form and arrangement of the several parts of my invention without departing from its spirit and scope. Therefore I desire to have it understood that I do not limit myself to the precise details shown and described or to the exact arrangement of parts herein set forth.

30 I claim as my invention—

1. In a sofa-bed, in combination, a supporting-frame composed of two end members, two upright members, a rear brace, and a cross-piece; a back having a link for connecting it 35 with each of said upright members; a seat having a pivotal connection with said back; a rail on each of said end members for supporting said seat; and a drawer having a link connection with the link supporting said back.

2. In a sofa-bed, in combination, a supporting-frame composed of two end members, two upright members, a rear brace, and a cross-piece; a back having two links, one for connecting it with each of said upright members; a seat having a pivotal connection with said back; means for releasably locking said seat and said back at an angle with each other; a 45 rail on each of said end members for supporting said seat; and a drawer having a link connection with each of the links for supporting said back.

3. In a sofa-bed, in combination, a supporting-frame; a back having a link for connect-

ing it with said frame; a seat; a hinge-joint between the seat and the back; a stud fixed to one member of said hinge-joint, said member also having a pawl pivoted thereon; and a locking-bar pivoted to the other member of 60 said hinge-joint, and adapted to engage said fixed stud, and having a tooth adapted to engage said pawl.

4. In a sofa-bed, in combination, a supporting-frame composed of two end members, two 65 upright members, a rear brace, and a cross-piece; a back having two links, one for connecting it with each of said upright members; a seat; a hinge-joint between the seat and the back; a stud fixed to one member of said hinge-joint, said member also having a pawl pivoted thereon; and a locking-bar pivoted to the other member of said hinge-joint, adapted 70 to engage said fixed stud, and having a tooth adapted to engage said pawl. 75

5. In a sofa-bed, in combination, a supporting-frame composed of two end members, two upright members, a rear brace, and a cross-piece; a back having two links, one for connecting it with each of said upright members; 80 a seat; a hinge-joint between the seat and the back; a stud fixed to one member of said hinge-joint, said member also having a pawl pivoted thereon; a locking-bar pivoted to the other member of said hinge-joint, adapted to 85 engage said fixed stud, and having a tooth adapted to engage said pawl; a drawer; and a link connection between the drawer and each of the links for the back for projecting said drawer. 90

6. In a sofa-bed, in combination, a supporting-frame composed of two end members, two upright members, a rear brace, and a cross-piece; a back having two links, one for connecting it with each of said upright members; 95 a seat; a hinge-joint between the seat and the back; a stud fixed to one member of said hinge-joint, said member also having a pawl pivoted thereon; a locking-bar pivoted to the other member of said hinge-joint, adapted to 100 engage said fixed stud, and having a tooth adapted to engage said pawl; a rail on each of said end members for supporting said seat; a drawer having a link connection with each of the links for said back; and guides in said 105 frame for said drawer.
